UNITED STATES PATENT OFFICE.

CARL E. NORIN, OF HARTFORD, CONNECTICUT, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,370,475.

Specification of Letters Patent.

Patented Mar. 1, 1921.

Application filed July 10, 1919. Serial No. 309,836.

To all whom it may concern:

Be it known that I, CARL E. NORIN, a citizen of the United States, residing in Hartford, in the county of Hartford and State of Connecticut, have invented certain new and useful Improvements in Combined Typewriting and Computing Machines, of which the following is a specification.

This invention relates to computing machines, and is herein shown as applied to an Underwood standard bookkeeping machine, one form of which is disclosed in the patent to Hart, No. 1,296,953, dated March 11, 1919, in which the machine is provided with an electric motor for carrying into the computing wheels digits set up by the numeral keys, and in which the carriage trips off the motor at the writing of the last digit of a number.

According to the present invention, the machine may be provided with a shutter or with a device for interfering with the operation of the keys, or with both. These may be normally ineffective, but may be tripped off by the same device which serves to trip off the motor, this device being shown in the Hart patent as a tabulating column-stop. Such shutters and key-interfering devices have usually been operated by a special dog, or else did not come into operation until the general operator which carries the digits into the wheels had already started to move. The present invention, therefore, provides that the wheels may be hidden and the keys may be obstructed at the time the motor should be operated, with the result that any failure on the part of the motor to start will make itself immediately manifest to the typist.

Other features and advantages will hereinafter appear.

In the accompanying drawings,

Figure 1 is a sectional side view of an Underwood standard bookkeeping machine, largely diagrammatic, and showing the present invention as applied thereto.

Fig. 2 is a fragmentary perspective, illustrating some of the motor-starting connections.

Fig. 3 is a skeleton perspective, showing the relationship of many of the principal parts of the machine which are related to the present invention.

Fig. 4 is a fragmentary perspective view

of a modified form of the connections for releasing the shutter or key-interfering device.

In the usual Underwood standard bookkeeping machine, numeral keys 10 and alphabet keys 11 depress key-levers 12 to cause bell cranks or sub-levers 13 to swing type-bars 14 upwardly and rearwardly, so that types 15 thereon print against a platen 16 which is journaled in a carriage 17. The carriage is normally under tension of a spring barrel 18, tending to draw it in letter-feeding direction along its rails 19 and 20, but it is held by the usual escapement loose dog 21, which is adapted to be actuated whenever a type-bar 14 approaches the platen. To effect this, each type-bar is provided with a heel 23, which, as it approaches the platen, strikes a universal bar 24 and swings it rearwardly, thereby making the usual solid dog 22 effective on the usual escapement wheel 25. On the return stroke of the key, the universal bar 24 springs forwardly and allows the dog 21 to reengage the escapement wheel 25, to permit the carriage to feed forward one letter-space. The escapement wheel 25 is connected to the usual pinion 26 by the usual pawls (not shown), and the pinion meshes with the usual pivoted rack-bar 27 connected to the typewriter carriage. In order to rapidly position the carriage at any desired point, there are provided the usual decimal-tabulating keys 28, which, in the usual manner, are adapted to release the carriage by lifting the rack-bar 27 through connections (not shown herein), so that it is drawn along until a column-stop 29 upon the carriage arrests the carriage by striking a counter-stop 30, connected in the usual way to its key 28. The column-stops may be of various forms, as well as that shown at 29, which will be described more fully herein, and are settable upon the usual rack-bar 31.

In order to enable computations to be effected, the machine is provided with the usual settable pins 32 upon pin-bars 33, which have racks at their forward ends adapted to turn the usual computing wheels 34 by pinions 35 connected with said wheels. The digits written by the numeral keys 10 in a computing zone are adapted to be set up by depressing the pins 32 in the usual way. To prevent setting up of the pins

32 at the wrong time, the pins are normally out of alignment with pin-setting bars 36, but are adapted to be shifted forwardly slightly by the setting forwardly of their respective pin-bars 33 *seriatim* by the usual denomination-selecting dog 37 upon the carriage. The connections for doing this setting forward include pivoted jacks 38 which are swung up, one at a time, by the selector 5 37, with the result that any jack when so swung carries down its rear end to depress the usual rod or wire 39, to rock the usual bell-crank-lever 40, which is effective through the transposing mechanism 41, to set forwardly the pin-bar connected to the jack 38, which is effective at the moment, so that the pins 32 thereon will be in alignment with the pin-setting bars 36. The key 10, depressed at this moment, sets the pin 10 corresponding to it on the pin-bar 33, by actuating its own pin-setting-bar 36, the key-lever 12 for this purpose being provided with a pendant 42, which, as it descends, strikes a wrist 43 upon a rock-shaft 44, which is normally connected to its own linkage or pin-setting bar 36. The connections are such that whenever a key 10 is depressed, its linkage 36 descends and sets the pin 32 which is then below it.

30 After the digits representing a number have been set up by the setting of pins 32 upon the pin-bars 33, the digits are carried into the computing wheels 34 by means of a general operator 45, which has a cross-bar 46 just below the pin-bars 33, with the result that it strikes any depressed pins, and carries forward the pin-bars to an extent depending upon the pins depressed, so that the numeral wheels 34 are turned to a corresponding extent. At the return stroke of the general operator, the cross-bar 46 strikes lugs 47 upon the pin-bars and carries the pin-bars back substantially to their normal position, so that they may be properly held 40 by detents 48 out of the way in the next pin-setting operation. The pins are restored, ready for such operation, by means of a mechanism, not shown herein, but one form of which is described in some detail in 45 Patent No. 1,278,812, dated September 10, 1918. The computing or numeral wheels 34 do not turn on the return stroke of the general operator, because they are provided with the usual pawl-and-ratchet connections 50 to the pinions 35, and are also provided with the usual detents (not shown). The usual carry-over mechanism (not shown) is also provided. As herein disclosed, the mechanism also comprises a subtraction-setting device, which includes a subtraction-setting pin-bar 49, which is adapted to alter the pin-setting connections in a manner set forth in said Patent No. 1,278,812.

60 The general operator is herein shown as 65 adapted to be automatically actuated by

means of an arm 50 connected to a motor (not shown) but under the control of an electric contact clutch 51, which is normally held by a starting pin 52. In some forms of the mechanism, the starting pin 52 is moved to ineffective position to start the motor by depressing a starting key 53, which overlies a motor-starting lever 54, connected at 55 to the starting pin 52.

According to the present invention, there 75 may be utilized the motor-starting mechanism of the Minton Patent, No. 1,280,065, which includes a lever 56, pivoted intermediate its ends at 57, and comprising a one-way dog 58 which is adapted to be struck 80 by a motor-starting projection 59 upon a column-stop, the connections being such that the dog 58 lifts the pin 52 when the stop 29 strikes it while traveling in letter-feeding direction. The connections between the dog 85 58 and the starting pin 52 include a draw-link 60, pivoted to the opposite end of the lever 56, and pivotally connected at its lower end to a bail 61, to which is fast a rock-arm 62. This rock-arm 62 has pivoted to it a 90 restraining arm 63, which normally overlies a spring-tensioned lever 64, in such a way as to prevent the actuation of the lever 64 by its spring 65. Whenever the starting dog 58, however, becomes effective, the 95 restraining arm 63 is withdrawn from the end of the lever 64, with the result that the spring 65 swings the rear end of the lever upwardly, thus carrying the front end 66 of the lever downwardly, so that it carries 100 down the starting key 53, and thereby starts the motor to actuate the general operator.

As set forth in said Hart patent, the lever 64 is adapted to be restored to its normal position by the actuation of the general operator, and, for this purpose, its end 66 comprises a bent-over arm 67 which overlies a cam 68, forming an extension at one side of the general operator, with the result that an advance of the general operator 110 raises the front end 66 of the lever 64 and lowers its rear end, so that the holding arm 63 is snapped back over it, by means of its spring 69.

The machine, as herein illustrated, 115 comprises a shutter 70 which is normally ineffective, but which is under the tension of a spring 71 which tends to make it effective, it being, however, restrained by a latch 72. The shutter is adapted to be made effective 120 by the actuation of the dog 58, and, to accomplish this, the latch 72 is shown in the form of a long bar 73, which has a limited motion to and fro upon a slide-pivot 74, and which is pivoted at its rear end to a 125 rock-arm 75, fast upon a cross-rock-shaft 76. The actuation of the dog 58 is adapted to rock the shaft 76, and, for this purpose, there is fast on the opposite end of said shaft a rock-arm 77, having an elbow 78 130

overlying the lever 64, with the result that whenever the lever 64 is released by the actuation of the holding arm 63, the latch 72 is drawn back by its spring 79, thereby permitting the spring 71 to become effective on the shutter. The connections between the spring 71 and the shutter include a bell-crank 80, upon which the spring 71 draws, said bell-crank having a forked arm 81 en- 10 gaging a pin 82 upon a rock-arm 83, fast upon a shaft 84, said shaft being connected to the shutter by means of a rock-arm 85, fast to the shaft and joined by a link 86 to one arm 87 of the shutter. To enable the 15 shutter to swing easily and properly to cover up the numbers upon the wheels 34, it is shown as pivoted upon the axle 88, upon which the wheels 34 are journaled.

The latch 72 is herein illustrated as not 20 only controlling the shutter, but as also controlling a key-interfering device.

The key-interfering device is herein shown as comprising a bar 89 which normally rests in the ineffective Fig. 1 position, lying be- 25 hind the numeral keys 10 and just above them. The bar 89 is supported upon stand- 30 ards 90 which are fast upon the shaft 84, their position being such that when the shutter is effective, the bar 89 stands over the numeral keys 10 and obstructs their op- 35 eration, while normally both the shutter and the bar 89 are ineffective. To restore the shutter 70 and the interfering bar 89 to their normal positions, there is provided a bell-crank 91, having an arm 92 which nor- 40 mally rests in a notch 93 in the side bar 94 of the general operator. Normally the bell-crank 91 stands clear of the arm 95 of the bell-crank 80, but when the general operator 45 comes forward, the arm 92 rides out of the notch 93 and swings the bell-crank upwardly, thereby causing the forked arm 81 to swing the arm 83 downwardly, thus mov- 50 ing the shutter 70 and the obstructing bar 89 to ineffective position.

In addition to the stop 29, which may serve for adding purposes, there may be provided other stops such as the stop 96 which is ineffective on the starting dog 58. 55 The stop 29 may be reversible and be cut away as at 97 so that it may play the part of a stop 96, if reversed. Certain tabulating stops may be adapted to automatically set the mechanism to subtraction as well as to start the general operator. For this purpose, the subtraction stops each comprise a body 98, which is like the body of the stop 29 and carries an extension 99 which is adapted to strike a one-way dog 100 upon a subtraction- 60 setting lever 101, pivoted at 57, like the lever 56, and which is connected by a draw link 102 to the usual subtraction-setting mechanism, one form of which is disclosed in said patent to Hart. The subtraction stop may 65 also comprise a lug 103, adapted to strike

the dog 58 to start the motor. Thus a single subtraction stop sets the mechanism to subtraction and starts the motor.

In Fig. 4 is shown an alternative form of the device, in which the holding arm 63 is 70 adapted to operate the shaft 76 directly without depending upon the lever 64. To accomplish this, the holding arm 63 is provided with a bent-off arm 105, forming a cam, which is drawn to the right in Fig. 4 75 and rocks the shaft 76 by carrying the cam arm 105 against a dependent arm 106 fast to the shaft 76, thereby rocking it just as does the arm 77.

Variations may be resorted to within the 80 scope of the invention, and portions of the improvements may be used without others.

Having thus described my invention, I claim:

1. In a combined typewriting and com- 85 puting machine, the combination with nu- meral keys and a traveling carriage, of a device for interfering with the operation of said keys, a computing device comprising members adapted to be set by said keys, com- 90 puting wheels, a drive for carrying into the wheels digits set up on said members, a car- rriage-operated link for starting said drive, and means operated by said link for mak- 95 ing said interfering device effective. 95

2. In a combined typewriting and com- puting machine, the combination with nu- meral keys and a traveling carriage, of a device for interfering with the operation of said keys, a computing device comprising 100 members adapted to be set by said keys, com- puting wheels, a drive for carrying into the wheels digits set up on said members, a set- table dog on said carriage, means operated by said dog for starting said drive, and 105 means operated by said dog for making said interfering device effective.

3. In a combined typewriting and com- puting machine, the combination with nu- meral keys and a traveling carriage, of a 110 device for interfering with the operation of said keys, a computing device comprising members adapted to be set by said keys, com- puting wheels, a drive for carrying into the wheels digits set up on said members, a set- 115 table dog on said carriage adapted to cause said wheels to add or subtract, a connection operated by said dog for starting said drive, and means controlled by said connection for making said interfering device effective. 120

4. In a combined typewriting and com- puting machine, the combination with nu- meral keys and a traveling carriage, of a device for interfering with the operation of said keys, a computing device comprising 125 members adapted to be set by said keys, com- puting wheels, a drive for carrying into the wheels digits set up on said members, a spring normally tending to make said in- terfering device effective, a catch for hold- 130

ing said device against the tension of the spring, a starting lever for said drive, carriage-controlled means for operating said starting lever, and means for releasing said catch including a bar overlying said starting lever so as to be actuatable thereby.

5. In a combined typewriting and computing machine, the combination with numeral keys and a traveling carriage, of computing wheels, a shutter for said wheels, a computing device comprising members adapted to be set by said keys, a drive for carrying into the wheels digits set up on said members, and a single member settable on 10 said carriage, adapted to start said drive and make said shutter effective.

6. In a combined typewriting and computing machine, the combination with numeral keys and a traveling carriage, of a device for interfering with the operation of said keys, a computing device comprising members adapted to be set by said keys, computing wheels, a drive for carrying into the wheels digits set up on said members, means, 25 including a holding arm, for keeping the drive ineffective, a catch for keeping the interfering device ineffective, catch-releasing means controlled by said arm, and carriage-controlled means for moving the holding 30 arm to release the drive and to make the catch ineffective.

7. In a combined typewriting and computing machine, the combination with numeral keys and a traveling carriage, of com-

puting wheels, a shutter for said wheels, a computing device comprising members adapted to be set by said keys, a drive for carrying into the wheels digits set up on said members, a drive-starting device, a tabulating device for said carriage, including a 40 stop, a member forming part of said stop adapted to cause said computing device to subtract, a member forming part of said stop adapted to render said drive-starting device effective, and means, controlled by 45 said drive-starting device, for shifting said shutter to effective position.

8. In a combined typewriting and computing machine, the combination with numeral keys and a traveling carriage, of computing wheels, a device for interfering with the operation of the keys, a computing device comprising members adapted to be set by said keys, a drive for carrying into the wheels digits set up on said members, a 50 drive-starting device, a tabulating device for said carriage, including a stop, a member forming part of said stop adapted to cause said computing device to subtract, a member forming part of said stop adapted to render said drive-starting device effective, and means rendered effective by said drive-starting device to render the key-interfering device effective.
